UNITED STATES PATENT OFFICE.

REINHARD KÖLSCH, OF PFORZHEIM, GERMANY, ASSIGNOR TO THE FIRM LOUIS KUPPENHEIM, OF PFORZHEIM, GERMANY.

LINK-FORMING MECHANISM.

Application filed June 29, 1920. Serial No. 392,897.

(GRANTED UNDER THE PROVISIONS OF THE ACT OF MARCH 3, 1921, 41 STAT. L., 1313.)

To all whom it may concern:

Be it known that I, REINHARD KÖLSCH, a citizen of the German Republic, of Pforzheim, Germany, have invented certain new and useful Improvements in Link-Forming Mechanism (for which applications for patent have been filed in Germany, July 21, 1916, Patent No. 321,075; Austria, August 16, 1917, Patent No. 84,568; Hungary, September 22, 1917, Patent No. 72,856; Switzerland, August 17, 1917, Patent No. 87,792; Great Britain, August 29, 1917, Patent No. 166,171; and France, August 30, 1917, Patent No. 515,003); and I do hereby declare the following to be a full, clear, and exact description of the invention, such as will enable others skilled in the art to make and use the same, reference being had to the accompanying drawings, and to reference characters marked thereon, which form a part of this specification.

This invention relates in general to a machine for the manufacture of rings, links, and meshes, which may either be connected with each other to form a chain, or a mesh-fabric, or may be singly employed for any purpose and in any manner whatever.

It is already known to produce rings and the like from an appropriately long or short piece of wire which is grasped by a pair of tongs by means of which it is shoved forward into a matrix or a bending stamp or punch wherein the piece of wire is bent into the shape of a ring.

In particular the invention relates to certain improvements in the means for cutting off the proper length of wire from the endless wire fed into the device, and for bending that piece of wire into the form of a ring which is completely closed except at the place of the joint where the wire ends may be united with each other in a separate stage, for instance by soldering or by welding.

In my present improved device the tools necessary for forming the piece of wire into a ring are combined with each other in such a manner that the piece of wire cut off from the supply wire cannot possibly fall out of the device because that wire piece is further worked, i. e., preliminarily bent, within a sleeve receiving and containing the respec-

tive tools, out of which it is shoved into a closing stamp completing the bending, or the formation of the ring respectively. 55

The device in question consists chiefly of a composite tool having an outer sleeve which holds the wire against a bending mandrel whilst a knife cuts off from the wire such a piece as is required for the formation of 60 a ring, link or mesh. Said sleeve contains small tongs provided with elastic cheeks and adapted to be displaced in the said sleeve whereby the piece of wire is bent around a mandrel forming it into U-shape. The thus 65 preliminarily formed ring or link is taken up by an appropriately shaped stamp located in said tong and co-operating with a semicircular member. After the bending-mandrel has disappeared, the stamp co-operating with the tongs pushes the thus bent wire-piece out of the sleeve and conducts it to the front of a suitably shaped closing stamp which grasps the wire-ends that now 70 have become free and makes them contact 75 with each other so as thereby to finish the ring or the like.

When manufacturing mesh-fabric the displacement of the half-finished ring toward the closing die may be used to cause the parallel ends of the U-shaped wire to first pass through two adjacent rings or meshes of the previously formed mesh fabric. 80

In order to make my invention more clear, I refer to the accompanying drawings in 85 which similar letters of reference denote similar parts throughout the several views and in which:

Fig. 1 is a side view of the machine for the manufacture of mesh-fabric, this machine being furnished with the invention in question; 90

Fig. 2 is a longitudinal section on line 2—2, Fig. 3;

Fig. 3 is a plan of the parts shown in 95 Figure 2; and

Figs. 4-6 show three different positions of the operating parts whilst producing the ring, some parts being shown in section.

The table 1 of the machine carries a support 2 for a main slide 3 upon which is mounted the main part of the new device, i. e., that for manufacturing the rings. The position of this device is shown in Figure 2 100

in dotted lines. The slide 3 is actuated by the double armed lever 5 which is fulcrumed at 4 to the table of the machine. The lower end of said lever is in contact with an eccentric disk 6 which is keyed to a shaft 7 rotated by any suitable means; said disk oscillates the lever 5. The upper end of this lever is forked and takes into a space 8 provided between adjusting rings 9 which may be displaced upon a bolt 10 carrying a coil spring 11 pressing, with the mediation of a washer 12, against the slide 3. The bolt 10 terminates in an auxiliary slide or glide piece 13 provided in the larger slide 3. The shaft 4 carries a crank arm *c* that is connected by a link *d* to an arm *e* on a shaft *f*. Shaft *f* carries an actuating arm *g* for a closing die 22.

To the slide 3 is attached, by means of a lateral arm 14, a small sleeve 15 which has wedge-shaped recesses 15^a at its sides and oblong recesses 15^b at its top and bottom. This sleeve holds the wire 16 which is moved forward by a feeding device comprising a bipartite box *a*¹—*a*² (Fig. 3) against the bending mandrel 17, whereafter a piece of wire as required for a ring is cut off by means of the knife *b*.

The sleeve 15 (Figs. 2 and 3) contains a small tongs 20 which may be displaced within the sleeve, and which consists of two elastic arms 24 that are fluted at their inner surfaces and are affixed to a small tube 25 secured to a small standard 26 connected by a screw-threaded pin 27 with a small slide 28 movably mounted upon the glide-piece 13. This slide forms at one end two small rails 29 which are connected with each other by a small screw-threaded bolt 30, in such a manner, that they are in a slight frictional contact with an upright lug 31 of the glide piece 13, said lug being slightly clamped in by said rails. The tube 25 of the tongs 20 and its standard 26 are, furthermore, guided upon the shaft of a die 23 provided within the tongs. Said die is inserted at one end in an appropriate bore of the slide 13 and carries a small standard 32 having a pin 33 upon which the standard 26 of the tongs 20 may be displaced. This connection between the tongs 20 and the die 23 serves only to prevent these parts from turning one with respect to the other.

The slide 3 has screwed to it two lateral plates 34, of which the front lateral lugs 36 and 36' take into recesses 35 of the slide 28. The lug 36 stops the front shoulder *h* and lug 36' stops the rear shoulder *i*, the plates 34 being slightly off-set to this end.

60 The operation of the device is as follows: From the position of rest shown in Figure 1 the slide 3 with all parts attached to it moves into the position shown in Fig. 2 in which the sleeve 15 holds the wire against the bending mandrel 17 whilst the piece of

wire necessary to produce the ring is cut off. The slide being further advanced, the piece of wire is forced by the mandrel into the sleeve until finally the parts have arrived in the position shown in Figure 4. In this position the piece of wire has been grasped by the tongs 20 and has been bent around the mandrel 17, the now U-shaped wire piece being received at its rear semi-circular part by the die 23. The mandrel 17 now moves out of the path of the sleeve and of the tongs which may be effected, for instance, by letting the bolt 21 Fig. 1 that supports the mandrel lever 18 move downwards, which may be done by any appropriate means that need not be shown and described.

The movement of the main slide 3 proceeds; the sleeve 15 with the tongs 20 and the die 23 advance the wire piece further until the slide 3 is stopped by a bolt 19 (Fig. 1) which is provided at the slide pushing against a projection (not shown) provided for this purpose. But as the oscillation of the lever 5 proceeds further in the same direction, only the slide 13 is further moved, the spring 11 being at the safe time compressed, so that now the tongs 20 is advanced owing to its connection with the slide by means of the parts 25, 26, 27, 28, 31, as is also the die 23, the U-shaped wire piece being taken along with the tongs and the die.

During the forward movement of the main slide 13, the tongs 20 and the die 23 advance from the end of the sleeve 15, (Fig. 5). If it be assumed that the mechanism is used in making ring mesh fabric, the two parallel ends of the partly formed wire blank are passed during this movement through two adjacent rings of such fabric. At this moment the movement of the tongs 20 is stopped when the rear edge of recess 35 strikes the lugs or stops 36' projecting into the recess, the main slide 3 carrying said lugs being at rest.

The slide 28 with it the tongs 20 being stopped, the slide 13 which is only in frictional contact with slide 28 continues its forward movement with the die 23. At this moment or preferably a little before it, the closing die 22 has been moved into operating position, Fig. 5, to engage the parallel ends of the wire blank and to also pass through the two adjacent ringlets that are to be joined together by the ringlet now being formed. As the die 23 continues its forward movement the parallel ends of the blank are closed by the die 22 which is now stationary, Fig. 6, and the shaping is finished, i. e., to a ring, link or mesh.

After this the dies 22 and 23, tongs 20 and sleeve 15 are moved back into their initial position, the spring 11 assisting the parts to return to initial position, Fig. 1.

The ring, link or mesh may then be advanced by any desired means preparatory to

the formation of a new link or ring which single lever operating to move the auxiliary means forms no part of the present invention and need not be illustrated or described.

Having now described my invention, what 5 I desire to secure by a patent of the United States is:

1. In mechanism for forming links and the like, a mandrel, a main slide, a sleeve thereon having lateral forks for holding a 10 wire length against said mandrel during cutting, an auxiliary slide movable on the main slide, a small slide frictionally connected with said auxiliary slide, wire embracing tongs in said sleeve mounted on said 15 small slide and a die member within said tongs mounted on said auxiliary slide.
2. In mechanism for forming links and the like, a main slide, a sleeve thereon having lateral forks holding a wire length 20 against mandrel during cutting, an auxiliary slide spring held in said main slide, a small slide frictionally connected to the auxiliary slide, tongs in said sleeve carried by said small slide, a die member within said 25 tongs mounted on said auxiliary slide and a

single lever operating to move the auxiliary slide and thereby the other two slides.

3. In mechanism for forming links and the like, a closing die, means to advance and retract said die from link forming position, in combination with a mandrel, a main slide, a sleeve thereon having lateral forks for holding a wire length against said mandrel during cutting; an auxiliary slide, spring connected to said main slide, a small 30 slide moved by said auxiliary slide, tongs in said sleeve carried by said small slide, a die member within said tongs mounted on said auxiliary slide, a single lever operating to move said auxiliary slide and thereby the 35 other two slides, and levers connected to the aforesaid lever and closing die means for simultaneous actuation.

In testimony whereof I have affixed my signature.

REINHARD KÖLSCH.

In the presence of—

MARIE DANZ,
KARL T. LUMM.
